FISHING LURE

Douglas W. Parker, 3015 Free Ferry,
Fort Smith, Ark. 72901

Filed July 11, 1968, Ser. No. 12,698

Term of patent 14 years

U.S. Cl. D22—28
Int. Cl. D22—07

Fig. 1.

Fig. 2.

Fig. 3.

Fig. 4.

Fig. 5.

Fig. 6.

FIG. 1 is a side perspective view of a fishing lure embodying my design;

FIG. 2 is a front elevational view of same;

FIG. 3 is a top plan view of same;

FIG. 4 is a bottom plan view of same;

FIG. 5 is a rear elevational view of same; and

FIG. 6 is a sectional elevation of same taken approximately along the line 6—6 of FIG. 3 in the direction of the arrows.

The dominant features reside in the solid line portions.

I claim:

The ornamental design for a fishing lure, as shown and described.
